UNITED STATES PATENT OFFICE.

EDWARD E. CLEMENT, OF WASHINGTON, DISTRICT OF COLUMBIA, ASSIGNOR TO THE TELEPHONE IMPROVEMENT COMPANY, OF ATTICA, NEW YORK A CORPORATION OF NEW YORK.

CALL-RECORDING SYSTEM FOR TELEPHONE-EXCHANGES.

1,089,394.

Specification of Letters Patent. Patented Mar. 10, 1914.

Application filed November 21, 1905, Serial No. 288,367. Renewed October 15, 1912. Serial No. 725,927.

To all whom it may concern:

Be it known that I, EDWARD E. CLEMENT, a citizen of the United States, residing at Washington, in the District of Columbia, 5 have invented certain new and useful Improvements in Call-Recording Systems for Telephone-Exchanges, of which the following is a specification, reference being had therein to the accompanying drawing.

10 My invention relates to call recorders for telephone exchange systems, and has for its object the production of a recorder of this class which will record the number of a calling line, and will indicate the fact that 15 the line called has answered or not. Preferably this call recorder is associated with some portion of the central office connective apparatus, and operates therefore in conjunction with any one of a plurality of sub- 20 scribers or other lines.

Briefly stated, the invention is as follows: In a common battery telephone exchange system each cord circuit is provided with a recorder which is normally inactive, but 25 starts up as soon as the cord is connected to a line, continuing its motion until a switch arm connected to the recorder reaches a terminal associated with the line, whereupon the recorder stops with a printing wheel 30 having the number of that line exposed in printing position. At the same instant a printing magnet is actuated to produce an impression of the number upon a tape or card. When the wanted subscriber answers, 35 the supervisory relay, temporarily associated with his line, works a second printing magnet to produce a special mark opposite the number on the tape, whereby the record shows the fact that the call was answered. 40 When the plugs are finally pulled by the operator the recorder is ready for another operation, the paper or card being fed forward, but the switch arm remaining in any position in which it may happen to be. 45

The mechanical features of my invention include the recorder itself and a method of mounting a plurality of recorders for an exchange. The mounting is preferably in iron racks, of the same type that are commonly employed for relays in telephone exchanges generally. It is made of sufficient height to take a number of the recorders

vertically, and these slid in on edge, in grooves, like rows of books in a book case.

Each recorder comprises a supporting 55 plate or frame, with a flange, upon which is carried a paper roll and an inking device. The flange determines the width of the space to be occupied by the entire recorder mechanism, and the frame carries the type wheel, 60 printing magnet, ratchet wheel and step magnet, all housed within this space. The paper ribbon or tape feeds in through a slot in the flange, under the type wheel, upon 65 guide rollers and so out, a feed roller controlled by the printing magnet serving to send it forward, step by step, as the device is operated.

My invention is illustrated in the accompanying drawings wherein:

70 Figure 1 is a diagram showing two subscribers' line circuits and a central office connecting circuit with a recording device attached thereto. Fig. 2 is a front view of the switch showing various working parts 75 and necessary attachments. Fig. 3 is a rear view of the switch showing the contact banks and wiper arms. Fig. 4 is an end view of the switch. Fig. 5 is a view of a portion of the frame with the recorders in 80 place.

Referring to Fig. 1, A and A' are two subscribers' stations shown as connected to a multiple switchboard wired up in accordance with the well known standard scheme 85 of two-wire multiple. Each substation is equipped with apparatus usual in common battery systems, which consists of a transmitter T, receiver R, hook H, ringer Q and condenser C. The line-wires from the two 90 substations terminate in a central office in similar apparatus, and therefore only one need be described. The line-wires 1 and 2 extend from the sub-station to the contacts n, n', of the cut-off relay N, where they are 95 normally extended, the first to the line relay M, and the second to ground. When the relay N is energized the line wires 1 and 2 are extended through to the contacts, j, j' of the answering-jack J by the wires 3 10 and 4. The cord-circuit consists of the answering-plug P, whose tip p is connected to the tip p' of the calling-plug P' by the strand 7, condenser C, and strand 9. The

sleeve p' of the plug P is connected to the sleeve p' of the plug P' by the strand 8, condenser C' and strand 10. Bridged across the strands 7 and 8 is a pair of supervisory relays S, S' , which jointly control the supervisory lamp s . Bridged across the strands 9 and 10 are the two supervisory relays S^2 and S^3 jointly controlling the lamp s^5 .

All of the arrangement so far described is old and well known, having been largely used in common battery installations. I have shown my invention in connection with this circuit because it happens to be a convenient system for illustration; but I do not wish to be limited thereby nor am I limited in practice to any particular type of system. My invention is well adapted for any of the common battery systems now known and used.

20 The type of switch I have chosen to illustrate is that employed quite commonly in automatic exchange systems according to present practice. Its essential features are a spindle carrying two contact wipers and 25 rotating to move said wipers over a series of fixed contacts arranged in a circle having a greater or smaller dimension according to the number of contacts. The circle with its contacts is called a bank or contact bank. 30 The spindle is rotated by means of a ratchet wheel mounted on it and a pawl vibrated by an electro-magnet. This spindle has no idle or normal position, that is the wiper can rest on any contact, for when the switch 35 itself is idle there is no connection of any kind with the wiper. Mounted on the spindle is a type wheel fixed so that when the wiper rests upon any particular line-contact the number of that line on the type wheel 40 will be opposite the tape.

Referring now to Fig. 1, Z is the selector switch having a spindle z^6 mounted for revolution in a foot-step but which may and practically will be in practice horizontal. 45 On this spindle are mounted the collars z^4 and z^{14} , carrying the wipers z^5 and z^{15} respectively, which extend out radially so as to sweep over the circle of contacts as the spindle rotates. At the upper end of the 50 spindle is a type wheel D, bearing on its periphery type numbers or characters raised in relief, there being a number or character on the wheel corresponding to each line having a multiple contact in the bank swept 55 over by the wipers. Opposite the type wheel is a printing magnet W shown as a solenoid magnet with an iron shell and a central plunger carrying the armature w^3 at one end and the printing platen w^5 at the other. 60 Between the platen and the type wheel lies the tape w fed from a roll or spider X, as shown above the wheel, down between the friction or feed rolls w^1 and w^2 . The feed of this tape is governed by the printing 65 magnet. As it is illustrated it is for sim-

plicity, this is accomplished by means of a spring extension arm w^3 attached to the armature and provided with a hook or toe which catches into teeth on the periphery of the feed-wheel w .

The circuits of my switch are very simple, and the connections to the cord and line-circuits are made without altering or interfering with any of their parts. Taps are taken off the sleeve side of each line and carried to the multiple contacts in the switches of its particular position, there being one switch to each operator's cord-circuit. The taps are also taken off the cord-circuit as follows: one from each of the normally opened contacts of the sleeve answering and calling supervisory relays, and one from the normally closed contact of the tip calling supervisory relay which forms one terminal for the supervisory lamp. These taps are the only necessary wires to be connected, no changes being made in the cord-circuit in any other way.

Referring now to Fig. 1 the sleeve side of the line No. 4 is connected in multiple to the contacts of the switches in its position by the wire 30. The contact s^7 of the relay S' is connected to one terminal of the relay S^4 , the other terminal being connected to ground. The contact s^9 of the relay S^3 is connected to one terminal of the magnet W^2 , the other terminal being grounded. The contact s^4 of the relay S^2 is connected to one terminal of the magnet W , the other terminal being grounded. The relay S^4 , whose circuit is controlled by the relay S' , jointly controls the stepping magnet S^6 and also connects one terminal of the relay S^5 to ground. This relay S^5 , which is normally connected to the wiper z^5 , actually picks out the calling line to which the cord circuit is connected. The relay S^7 connected to the wiper z^{15} acts as a test relay, that is in passing over a row of contacts and resting on those which are busy it becomes energized, 100 attracts its armature, disconnecting the relay S^5 from its wiper z^5 . This is done to prevent the subscribers who are talking from receiving annoying clicks as the wiper z^5 passes over its contacts. When a line is busy its test contact z^{25} will be grounded, thereby 105 operating the relay S^7 as the wiper z^{15} comes in contact with it. The magnet S^6 is jointly controlled by the relay S^4 and the relay S^5 , that is, it is energized or started by the relay S^4 causing the spindle z^6 carrying the wipers to rotate. The relay S^5 opens its circuit when the wanted line is found, thus 110 causing the spindle to stop and the wipers rest on the calling line. This is a self locking relay and when energized disconnects the wiper z^5 leaving it free so as to leave the sleeve side of the line free from any discharge. The magnets W and W^2 jointly 115 control the tapper w^6 fastened to the spring 120 magnet. As it is illustrated it is for simplicity, this is accomplished by means of a spring extension arm w^3 attached to the armature and provided with a hook or toe which catches into teeth on the periphery of the feed-wheel w .

w^a and held rigidly in place by the block w^4 . The tapper w^6 when operated upon the called subscriber answering his telephone strikes the tape and prints some character 5 so as to show that the called subscriber has answered. The printing magnet W can only become energized when the relay S^5 is operated upon finding the calling line.

The operation of my system is as follows: 10 Subscriber A in calling closes the circuit of the relay M through the contact of the cut-off relay N closing the local circuit of the line lamp m which glows. The operator upon perceiving the signal inserts the answering plug P into the jack J . The windings of the relays S' and N are now connected in series. The relay N becoming energized attracts its armature, disconnects the line relay M which in turn extinguishes the 15 line lamp m . The line wires 1 and 2 are now connected to the springs j and j' respectively of the jack J through the contacts of the cut-off relay N and the extensions 3 and 4. The relay S' becoming energized 20 attracts its armature and would cause the lamp s to glow, but the relay S becoming energized at this time opens the lamp circuit. The circuit of the relay S^4 is now closed by the following path: battery B , 40, 12, 11, 41, s^6 , s^7 , 13, S^4 to ground. This 25 relay becoming energized attracts its armature and closes the circuit of the stepping magnet S^6 by the following path: battery B , 17, s^{10} , s^{11} , 16, G , which is the interrupting machine, S^6 , 24, s^{10} , s^{18} , to ground. The 30 magnet S^6 now operating causes the shaft z^6 to rotate and the wipers z^6 and z^{15} to pass over the contacts in the bank. The circuit of the relay S^6 , which picks out the calling 35 line, is now connected from the wiper z^6 to ground by the following path: 22, s^{20} , s^{21} , s^{15} , s^{16} , S^5 , 18, s^{12} , s^{13} to the ground. In passing over the contacts the wiper z^{15} in resting on one which is grounded or busy 40 immediately closes the circuit of the relay S^7 which attracts its armature, opens the contacts s^{20} and s^{21} , disconnecting the relay S^5 from the wiper z^6 thus preventing the subscribers from receiving a click. The 45 wiper z^5 which is connected to ground through the relay S^5 in passing over contacts which are not busy simply finds grounds through the cut-off relay N while the wiper z^{15} in passing over contacts that 50 are not busy finds no connection whatever, so the spindle keeps rotating. However, when the wiper z^5 finds a contact on which there is battery the relay S^5 immediately becomes energized and disconnects the stepping magnet S^6 . Suppose for instance the 55 wiper in passing over the row rests on the contacts leading to the line to which the cord-circuit is connected, the circuit of the relay S^6 would therefore be closed by the 60 following path: ground, s^{13} , s^{12} , 18, S^5 , 27, 65

s^{16} , s^{15} , 19, s^{21} , s^{20} , 22, z^5 , z^{10} , 30, 4, j' , p' , S' , 41, 11, 12, 40, to battery B . This relay now becoming energized attracts its armatures, closes the contacts s^{14} and s^{16} before breaking the contacts s^{16} and s^{15} thereby locking itself by the following path: B, 40, 17, 20, s^{14} , s^{16} , S^5 , 18, s^{12} , s^{13} , to ground. It also opens the contacts s^{19} and s^{18} disconnecting the stepping magnet S^6 and closes the contacts s^{18} and s^{17} placing a ground on the test wiper z^{15} and from there to the contacts z^{25} making them busy. The circuit of the printing magnet W is now also closed by the following path: B, 40, 17, 20 s^{14} , s^{16} , 27, 26, W to ground, and becoming energized presses the tape against the type wheel D and printing thereon the number of the calling line. In the mean time while the switch is operating the operator opens her listening key and asks the number wanted in the regular way. Upon finding the number desired she places the calling plug P' into the jack J' of the wanted line and rings in the ordinary manner. The insertion of this plug places the relays S^3 and N in series. The relay N attracting its armature disconnects the line relay M and connects the line wires to the springs j and j' of the jack J' . The relay S^3 becoming energized attracts its armature and closes the circuit of the lamp s^6 causing it to glow. The circuit of the magnet W^2 is closed by the following path: B, 40, 12, 11, 41, s^8 , s^9 , 15, W^2 to ground. The circuit of the magnet W' is also closed through the contacts s^3 and s^4 of the relay S^2 . The called subscriber upon answering closes his line circuit and energizes the relay S^2 which attracts its armature extinguishing the lamp s^5 notifying the operator that he has answered. The circuit of the magnet W' is also broken and the hammer w^6 which has been held by this magnet is released and under the tension of the spring w^a strikes the tape and prints thereon a character which shows that the 90 called subscriber has answered. We now have on the tape a record showing the number of the calling line and also that the party that he called answered. Suppose the called party did not answer; the operator 95 after a reasonable length of time would take down the connection and the magnets W' and W^2 would become deenergized at the same time and the armature w of the magnet W^2 would engage the spring w^a and 100 prevent the tapper w^6 from striking the tape, thereby preventing a record of a call being answered when the party called for did not respond. In other words the only time the record could be made for an 105 answered call would be when the magnet W^2 was energized and the magnet W' deenergized. This can only happen when the calling plug is in the jack and the called party 110 answers. At the end of the conversation 115

the operator upon getting the disconnect signal withdraws both plugs from the jacks opening the circuit of the relay S^4 which in turn releases the relay S^5 which is again connected to the wiper z^5 and all the other parts of the switch are restored to their normal position

The mechanical parts of my recording device are shown in Figs. 2, 3, 4 and 5. It will be noticed that the form shown in these figures is not the same as that shown in Fig. 1 but it will be understood that either of the forms of the device may be used in connection with the recording system. Referring to these figures, O is the frame or side plate having the front flange O' . The bank contacts of the recorder switch are mounted on one side of the plate, and the working mechanical parts, including the ratchet wheel and printing wheel, are mounted on the same spindle on the other side of the plate. On the flange O' is a supporting bracket carrying the spool X for the paper roll or tape x . This tape is fed in through a slot in the flange O' , over the guide roller w^{10} , other guide rollers w^9 , w^8 and w^7 , the feed roller w' , and the friction roller w^2 , and so out through another slot, which is preferably a little out of line with the paper roll, for a reason which will presently be mentioned. In Fig. 3 I have shown the bank contacts. The spindle z^6 extends through the plate from side to side, and carries the wiper arms z^5 , z^{16} , which play over the line contacts z^{10} and z^{25} , shown in Figs. 3 and 4. These are preferably German silver terminals clamped between brass plates by screws z^{40} , and insulated by means of the interposed rubber or fiber rings z^{50} , z^{60} and z^{70} , the outer ring z^{30} being of brass. Upon the other side of the plate O the spindle z^6 is journaled in the bracket H , inside of which it carries the type wheel D , and outside of the bracket carries the ratchet wheel z' . This ratchet wheel is stepped around by means of a pawl l' pivoted at l^2 on the lever L , adapted to be attracted by the stepping magnet S^6 , which is mounted on a bracket s^{30} , secured to the plate O . The stop s^{20} is provided for the pawl l' to limit its play in the forward direction, and the lever L is provided with a retracting spring l which normally holds it against a back stop F comprising a thumb-screw threaded into a post P and provided with a lock nut f . The printing magnet W is mounted on a bracket w^{30} , and has its printing arm w^{40} , carrying the platen w^{50} , pivoted at w^{60} , with a retracting spring w^{20} . Upon the armature of this magnet is secured a spring pawl which takes into ratchet teeth on the feed roller w' , so that each time the magnet is energized the paper is fed forward one step. The reason I prefer to have the slot through which the paper passes out to one side of

the middle line, is that when the recorders are all mounted up in the rack the paper tape coming out should be allowed to fall clear of the paper feeding in. This, however, is not essential. An opening in the flange O' receives a plug with a handle R , and on the inner end of this plug I mount an inking roll r , composed of felt or other material saturated with printers' ink. In Fig. 5 is shown a section of the frame as it appears when all the recorders are in place. It will be observed that an attendant or inspector can walk along in front of the rack and tell at a glance the condition of the paper rolls, whether the paper feed is working right, and by pulling out the plugs R can inspect the condition of the ink rolls. He can also watch the tapes to see if the numbers are being properly printed, and all this without taking any of the machines from the rack.

Many changes will doubtless be made in this apparatus, and some changes in the circuits, during commercial use, and while I have described the best embodiment I have thus far found for my invention, it is, of course, to be understood that I recognize and consider all non-essential changes as within the scope of the invention.

Having described my invention, what I claim and desire to secure by Letters Patent is:

1. In a call recording system for telephone exchanges and the like, a plurality of lines to be interconnected, means for interconnecting the same, a recording member carrying indicia corresponding to the circuits over which calls are to be recorded, means for moving said member, controlled in making connection with a calling line, and means for effecting a record when the recording member has been moved to expose the indication of the particular line with which connection has been so effected, and means for disabling the device for all other positions and for all other lines, whether calling or not.

2. In a telephone exchange system, a plurality of lines, means for interconnecting the same, and a recording system therefor, comprising a driven type wheel, a cooperating printing magnet, a motor magnet, a starting relay energized when connection is effected with a calling line and a stopping relay energized when the type wheel has been moved to expose an indication corresponding to the particular line in which connection has been effected.

3. In a telephone exchange system, a plurality of lines, means for interconnecting the same, and a recording system therefor, comprising a selector switch having a spindle carrying a type wheel and a contact arm, contact banks for said arm containing terminals for a plurality of lines, each con-

- 5 nected so as to have its potential raised when its line is calling, a motor for the switch, a starting magnet for the motor, connections for said starting magnet completed for its energization when connection is effected with a line, and a stopping magnet for the motor connected to the switch-arm and energized when the latter touches the contact of the line with which connection has been established.
- 10 4. In a telephone exchange system, a plurality of lines, means for interconnecting the same, and a recording system therefor, comprising a selector switch associated with a connective circuit, a spindle for said switch carrying a printing member and a contact arm, a series of line-contacts adapted to be swept over by said arm, line-numeral characters on said printing member corresponding in position with the line contacts, so as to be brought into printing position when the switch-arm rests upon their respective contacts, a motor for the switch, a controlling magnet for said motor, means whereby
- 15 20 25 30 35 40 45 50 55 60 65 70 75 80 85 90 95 100 105 110 115 120 125 130
- said controlling magnet is energized to start the switch upon connection being effected with a line, means to stop the motor when the switch-arm rests on the contact of the line with which connection has been established, and means to prevent interference with other busy lines.
5. A register system for telephone exchanges and the like comprising a selector switch and a recorder associated therewith, line-contacts and test-contacts in said switch, a motor for the switch a connective circuit, a starting magnet for the motor taking current through said connective circuit when the same is connected with a line, a stopping magnet connected to a switch-arm cooperating with the line-contacts, and adapted to become energized when its switch-arm rests on the contact of a busy line, and a test or guard magnet connected to a switch-arm coöperating with the test contacts and acting to disable the stopping magnet when its arm rests on a busy line-contact of any other line than that with which the associated connective circuit is in connection.
6. In a telephone exchange system, a plurality of lines, means for interconnecting the same and a recording system therefor, comprising a selector switch having a motor, a recording member, a line-testing member, and a busy-testing member, together with means to start the switch when connection is established with any particular line, means to stop the switch upon reaching a line which tests busy, and means to disable the stopping means for any other line than the particular line which is being sought.
7. In a telephone exchange system, a plurality of lines, means for interconnecting the same and a recording system therefor com-
- prising a selector switch having bank contacts associated in pairs, one contact of each pair connected to a particular line, and the other normally disconnected, means to change the condition of the line contacts when their lines are busy, means to move the selector switch to test the pairs of contacts in succession, and to stop the switch when a busy contact is found, and means to test the test-contacts in succession and to disable the stopping means when a busy test-contact is found other than that of the line sought.
8. In a recording system for telephone exchanges, a plurality of line-contacts, a plurality of connective circuits, a recording mechanism for each connective circuit comprising a recorder and a selector switch, bank contacts in each selector switch for the lines, test contacts associated therewith, means for raising the potential of the multiple contacts of a busy line in the switch banks, means for changing the condition of the test contacts corresponding to a busy line after the same has been selected and its number recorded, and double testing means associated in the control of each switch, the first test being made of the line-contacts and the second test being made of the test-contacts, a controlling magnet for the switch energized when connection is established with a particular line through its associated connective circuit, the line testing means responding and becoming effective to stop the switch when any busy line contact is found, but the second testing means acting to disable the first and prevent the stopping of the switch on busy contacts of other lines than that with which connection has been effected.
9. A recording system for telephone exchanges comprising the following instrumentalities: a selector switch having the recording member D, line-contacts z^{10} , test contacts z^{25} , and a pair of switch-arms co-operating with said contacts, a motor for the switch, a starting magnet controlling the said motor, a test magnet S' controlled by said starting member and connected to the second switch-arm, a stopping magnet S controlled in part by the starting magnet and in part by the test magnet, and acting when energized to stop the motor and change the condition of the test contact upon which the second or test arm is then resting.
10. In a recording system for telephone exchanges, the combination of the following instrumentalities: a plurality of subscribers' lines, a plurality of interconnecting or switching circuits, a plurality of selector switches associated therewith, each switch having a printing member D, a spindle z^6 and a pair of test arms z^5 and z^{15} , with line-contacts z^{10} and test contacts z^{25} coöperating with said arms, a motor S' for

the switch, a recording magnet W, a starting magnet S⁴ energized from the switching circuit when the latter is connected with a line, a test magnet S⁷ controlled on one side

5 by the starting magnet, and connected on the other side to the arm z¹⁵, and a stopping magnet S⁵ controlled jointly by the starting and the test magnets and connected to the switch-arm z⁵, said recording magnet being

also controlled by the stopping magnet, all 10 substantially as described.

In testimony whereof I affix my signature in presence of two witnesses.

EDWARD E. CLEMENT.
